UNITED STATES PATENT OFFICE.

RALPH R. ROOT, OF CLEVELAND, OHIO.

CONNECTOR.

1,269,748.

Specification of Letters Patent. Patented June 18, 1918.

Application filed June 14, 1915. Serial No. 33,857.

To all whom it may concern:

Be it known that I, RALPH R. Root, a citizen of the United States, residing at Cleveland, in the county of Cuyahoga and State of Ohio, have invented a certain new and useful Improvement in Connectors, of which the following is a full, clear, and exact description.

This invention relates to an electric connector. The object of the invention is to provide a connector more particularly adapted for use in connection with certain parts of the lighting circuit on an automobile, whereby an external circuit may be introduced into the usual circuit, which external circuit may contain a lamp or other electrical device.

Generally speaking, the invention comprises the elements and combinations thereof set forth in the accompanying claims.

Reference should be had to the accompanying drawings forming a part of this specification, in which Figure 1 is a side elevation showing the manner of use of the connector in the lighting circuit of an automobile, and illustrating one use to which the external circuit may be put; Fig. 2 is a sectional elevation of the connector; Fig. 3 is what may be termed a front elevation of the connector; and Fig. 4 is a rear elevation of the connector.

The connector herein described is particularly designed for the purpose of enabling a trouble lamp or handy lamp to be connected in the lighting circuit upon an automobile. Some makers of automobiles provide a socket adapted to receive a plug forming the terminal of a circuit which is especially adapted to accommodate a handy lamp or trouble lamp, but for the most part automobile manufacturers do not provide any means for using this device. Consequently, if such a device be used on an automobile it must be inserted in the circuit at some point which is accessible and convenient.

Many of the automobiles have a circuit for lighting lamps of the automobile which is known as the "one-wire circuit", that is to say, each of the lamp sockets upon one side is grounded to the frame of the vehicle, which forms the return path for the current, the current being introduced into the lamps by means of a single wire.

The connector of this invention is more particularly designed for use in connection with such a "one-wire system" and when

used as hereinafter set forth it eliminates the necessity for removing a lamp from the headlight or other light, and the insertion of a plug of the ordinary socket, as would be the case under usual circumstances. While, of course, it is perfectly possible to remove the lamp from a headlight and insert a socket, such a procedure necessitates removal and care of the lamp while removed, and, furthermore, it requires that the front part of the headlight be removed while the plug is inserted.

By the use of the connector of this application it is unnecessary to remove the lamp from the headlight, or, in fact, to open the headlight at all.

In the drawing, 1 represents a headlight which is adapted to house a lamp, it being understood that this headlight is of the "one-wire system" type heretofore described. At 2 is represented the cable by which electricity is introduced to the lamp, it being understood that one side of the lamp is grounded so that the return circuit is through the frame. 3 represents a usual plug used in connection with such lighting circuits, and 4 is the socket into which the plug 3 is normally secured. At 5 is generally represented the connector by which current through an external circuit generally represented at 6 is established. I have shown a trouble lamp as the electrical device energized by this external circuit. This trouble lamp comprises an electric light 7 carried by a reflector and support 8. In the particular instance there is provided a base 9 within which is a coil, so as to make the base in effect an electro-magnet, so that when the base 9 is energized the base may be set against any iron part of the vehicle and will be held in place by the magnetic field in a manner which will be well understood. At the same time the lamp 7 is receiving current so that the lamp is lighted.

The connector forming the subject matter of this application comprises a casing 10, having an arm 11. The arm 11 has two projecting lugs 12, so that it may be inserted and held in a socket of the usual construction. The casing 10 is provided with right angle slots 13, which are of usual form to receive a plug. For purposes of reinforcing the interior portion of the arm 11 I have shown a plug 14 made of insulating material.

Within the casing 10 there is a body 15 of insulating material. This insulating ma-

material has a central opening through which extends a conducting element 16. This element 16 at its lower end is recessed and receives a plunger 17. The plunger is held within the recessed element 16 by means of a head 18. Between the plunger 17 and the end of the recess in the element 16 there is a spring 19 which normally urges the plunger 17 in an outward direction. At the end of the element 16, opposite that which has just been described, there is a cup-shaped depression 20 and a recess 21. Into the cup-shaped depression 20 extends a conductor 22 and the skinned end of the conductor extends into the recess 21. The element 16 is provided with an opening adapted to receive a screw 23 which is adapted to engage the end of the conductor 22 to hold the same. The screw 20 extends through an opening 24 in the body 15.

The conductor 26, which together with the conductor 22 forms the two sides of an external circuit, is provided with a head 27. Through the head there extends a screw 28. This screw co-operates with an opening formed in the casing 10 and in the body 15, the screw 28 serving the double purpose of securing the head 27 to the casing 10 and holding the body 15 with respect to the casing 10.

When the connector is used the plug 3 is removed from its socket 4, the arm 1f of the connector is inserted in the socket 4 while the plug 3 is inserted in the casing 10 in the manner illustrated in the drawings. It will thus be clear that under these circumstances a circuit through the lamp 7 will have been established. If we conceive that current is being supplied through the conductor 2, the current will pass to the head 17, element 16 and conductor 22 to the device inserted in the external circuit, thence to the conductor 26 and to the casing 10. Through the casing 10 current will pass to the socket 4 which is grounded to the metal parts of the automobile and so forms a return circuit to the battery.

While the connector herein described is particularly intended for use in a manner which is herein described, I do not wish to

limit myself to its use entirely in this connection, as there are undoubtedly other uses to which the connector may be put with equal facility.

Having described my invention, I claim: 55

1. A connector comprising a sleeve-like body portion having socket slots in one end thereof, an extension from said body portion provided with projections which are adapted to co-operate with a socket, a body 60 of insulating material within the body portion, a terminal member extending through said body of insulating material, means for securing a conductor to the terminal, and means for connecting a second terminal to 65 the body portion, and in electrical connection with the extension before mentioned.

2. A connector comprising a body portion with a part thereof formed as a socket, said connector having another portion formed as 70 a plug, a body of insulating material forming part of the connector, a terminal member mounted in said body of insulating material, the terminal member extending adjacent the socket portion of the connector, 75 means for securing a conductor to said terminal member, and means for securing a terminal member upon the connector and in electrical connection with the plug portion thereof. 80

3. A connector comprising a body portion of metal and an extending arm of metal, the said arm being provided with projections which are adapted as a plug, a portion of the body end of the connector being formed 85 with the slots which adapt it to act as a socket, insulating material within the body portion, a connector extending through the insulating material, said connector co-operating with the socket portion of the body 90 portion, means for connecting a conductor to the terminal member, and means for connecting a conductor to the body portion and in electrical connection with the said arm.

In testimony whereof, I hereunto affix my 95 signature in the presence of two witnesses.

RALPH R. ROOT.
